UNITED STATES PATENT OFFICE.

CLEMENS E. EHN BORN, OF CHICAGO, ILLINOIS.

SPOOL.

1,346,117.

Specification of Letters Patent. Patented July 13, 1920.

Application filed October 22, 1919. Serial No. 332,426.

To all whom it may concern:

Be it known that I, CLEMENS E. EHN BORN, a citizen of the United States, and a resident of the city of Chicago, county of Cook, and State of Illinois, have invented 5 certain new and useful Improvements in Spools, of which the following is a specification.

My invention relates to improvements in spools, and has for its object the provision of an improved construction of this character providing a composite spool of simple construction and strong and durable in use.

Other objects will appear hereinafter.

The invention consists in the combinations and arrangements of parts hereinafter described and claimed.

The invention will be best understood by reference to the accompanying drawings 0 forming a part of this specification, and in which,

Figure 1, is a side view, shown partially in section, of a spool embodying the invention,

Fig. 2, an end view of said spool,

Fig. 3, a detail view of one end of the spool illustrating the form and arrangement of the parts at a preliminary stage of the manufacture,

Fig. 4, a perspective view of one of two filler heads employed in the construction,

Fig. 5, a detail view of one of two locking rings employed in the construction, and

Fig. 6, a detailed section of a slightly modified form of construction.

The preferred form of construction, as illustrated in the drawings, comprises a central hub 6 of wood or the like, and having reduced cylindrical projections 7 at each end, there being a peripheral locking groove 8 formed at the base of each projection.

Sheet metal flanges 9 are secured to each projection 7, said flanges being provided with central hubs 10 adapted to fit snugly over said projection 7, as indicated. After the hubs 10 have been placed in position over projections 7, the inner portions of said hubs are spun inwardly into the corresponding groove 8 and a split locking ring 11 is forced over each flange hub and is seated in each groove thus formed therein, the groove being deep enough, as shown, to accommodate said locking ring and bring its outer periphery flush with the outer periphery of the flange hub. Then, filler heads 12, of

wood or the like, and having central bores 13, are fitted over the flange hubs and locking rings, as shown. Each of the flanges 9 is provided with a peripheral flange 14 fitting snugly about the periphery of the corresponding filler head 12, and the filler heads are further secured in place by spinning the extreme edges 15 of the flanges 14 over the edges of the filler blocks, as shown.

In the modified form of construction illustrated in Fig. 6, the flanges 9 are provided with hubs 14 shorter than the projections 7, said hubs 14 being spun into peripheral grooves in said projections and held in place by the filler blocks 12, as shown.

By this arrangement, a composite spool is provided which may be made of considerable size, is light in weight and strong and durable in use.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. A spool comprising a hub of wood or the like having a reduced cylindrical projection at each end, there being a peripheral groove at the base of each projection; sheet metal flanges having central hubs fitted snugly over said projections and spun into said grooves; and rings seated in the grooves thus formed in the hubs of said flanges, substantially as described.

2. A spool comprising a hub of wood or the like having a reduced cylindrical projection at each end, there being a peripheral groove at the base of each projection; sheet metal flanges having central hubs fitted snugly over said projections and spun into said grooves; and split rings seated in the grooves thus formed in the hubs of said flanges, substantially as described.

3. A spool comprising a hub of wood or the like having a reduced cylindrical projection at each end, there being a peripheral groove at the base of each projection; sheet metal flanges having central hubs fitted

snugly over said projections and spun into said grooves; split rings seated in the grooves thus formed in the hubs of said flanges; and filler heads having central bores fitted snugly over the hubs of said flanges and said split rings, substantially as described.

4. A spool comprising a hub of wood or the like having a reduced cylindrical projection at each end, there being a peripheral groove at the base of each projection; sheet metal flanges having central hubs fitted snugly over said projections and spun into said grooves; split rings seated in the grooves thus formed in the hubs of said flanges; and filler heads having central bores fitted snugly over the hubs of said flanges and said split rings, said flanges being provided with peripheral flanges spun over the edges of said filler heads, substantially as described.

5. A spool comprising a hub of wood or

the like, having a reduced cylindrical projection at each end, there being a peripheral groove at the base of each projection; and sheet metal flanges having central hubs fitted over said projections and spun into said grooves, substantially as described.

6. A spool comprising a hub of wood or the like having a reduced cylindrical projection at each end, there being a peripheral groove at the base of each projection; sheet metal flanges having central hubs fitted over said projections and spun into said grooves; and filler heads having central bores fitted snugly over said projections and hubs, substantially as described.

In testimony whereof I have signed my name to this specification in the presence of two subscribing witnesses.

CLEMENS E. EHNBORN.
